UNITED STATES PATENT OFFICE.

ROBERT B. CARSLEY, OF NEW BEDFORD, MASSACHUSETTS, ASSIGNOR TO
THE TRIUMPH HEAT AND LIGHT COMPANY, OF PORTLAND, MAINE.

BURNER.

SPECIFICATION forming part of Letters Patent No. 397,630, dated February 12, 1889.

Application filed May 22, 1888. Serial No. 274,658. (No model.)

To all whom it may concern:

Be it known that I, ROBERT B. CARSLEY, of New Bedford, county of Bristol, State of Massachusetts, have invented an Improvement in 55
5 Burners, of which the following description, in connection with the accompanying drawings, is a specification, like letters on the drawings representing like parts.

This invention has for its object to provide a 10
10 portable burner of novel construction adapted to burn gas or vapor fuel, my improved burner being constructed as will be described, whereby substantially perfect combustion is obtained, thereby securing a maximum amount 15
15 of heat with a minimum consumption of fuel, either gas or hydrocarbon vapor.

My invention therefore consists, essentially, in the combination, with an inner and outer foraminous tube, of a muffle covering said 20
20 tubes and a base constructed to admit gas and air to the said tubes, the said gas and air being caused by the said muffle to pass through the sides of the said tubes, substantially as will be described.

25 Other features of my invention will be pointed out in the claims at the end of this specification.

Figure 1 is a vertical section of a single portable burner embodying my invention; 30
30 Fig. 2, a top or plan view of the base portion of the burner shown in Fig. 1; Fig. 3, an under side view of the burner shown in Fig. 1; Fig. 4, a detail of the muffle; Fig. 5, a top or plan view of a portable burner comprising a 35
35 group of burners shown in Fig. 1, and Fig. 6 an under side view of the burner shown in Fig. 5.

Referring to Fig. 1, the base portion of my improved burner consists, essentially, as herein 40
40 shown, of three parts—viz., first, an outer cup-shaped shell, a , having in its bottom a' an opening, a^2 , the walls of which project, as herein shown, above the bottom a' to form a flange, a^3 , preferably octagonal in shape; second, an inner shell, a^4 , preferably made as the 45
45 frustum of an octagonal pyramid to fit over the flange a^3 , to which it is luted or otherwise secured, as indicated by heavy line at a^5 ; and, lastly, a cap or cover, a^6 , having its under face 50
50 provided with a groove, into which the upper edge or rim of the shell a is fitted and ren-

dered gas-tight by luting a^7 , the upper portion, a^8 , of the said cap or cover being made, as shown, as a frustum of a pyramid to correspond with the inner shell, a^4 , and being provided with a flange, a^9 , which is luted, as at 55
55 a^{10} , to the inner shell, a^4 , the flange a^9 being provided with perforations or holes a^{12} , (see Fig. 2,) which constitute gas-outlets for the chamber B, formed by the outer shell, cap, 60
60 and inner shell. The outer shell is preferably supported upon a suitable pedestal, b , to which the cover a^6 is secured, as shown, by screw-bolts b' .

The base portion of the burner has secured 65
65 to it an inner tube or pipe, b^2 , and an outer tube or pipe, b^3 , preferably of foraminous metal, the inner tube being extended into the inner shell, a^4 , and being supported, as herein shown, by the flange a^9 , two or more sides of 70
70 the inner tube being pressed or bulged outwardly, as at b^4 , to rest upon the flange a^9 . The outer tube is fitted over the upper portion of and is supported by the cap or cover a^6 .

The burner is preferably provided with a 75
75 muffle, herein shown as a metal plate, b^5 , provided with lugs or projections b^6 , which extend down between the inner tube, b^2 , and the outer tube, b^3 , to secure the muffle on the burner.

80 The gas or vapor fuel is supplied to the chamber B through a pipe, c , in the outer shell. The gas or vapor fuel passes from the chamber B through the outlets a^{12} and up between the inner and outer tubes.

Air to support combustion is admitted into the burner, as shown, through the opening a^2 , and to regulate the amount of air to the amount of gas or vapor fuel supplied to the burner I have provided a suitable damper, c' , 90
90 (see Figs. 1 and 3,) pivoted, as at c^2 , to the bottom a' of the outer shell, the said damper having, as herein shown, three holes, 2 3 4, of varying size to vary the amount of air admitted to the burner. For instance, if it is 95
95 desired to admit a full or maximum amount of air, as would be the case if a full or maximum supply of gas is admitted to the burner, the valve would be turned, as by the handle c^3 , to place the hole 2 in line with the opening a^2 , it being of substantially the same size 100
100 as the said opening.

If it is not desired to use the maximum amount of gas, the supply may be controlled accordingly and the damper turned to place the hole 3 in line with the opening a^2 , and if 5 a minimum amount of gas be supplied to the burner the damper will be turned to place the hole 4 in line with the said opening.

By means of the damper c' the amount of air admitted to the burner may be regulated 10 to the amount of gas supplied to produce substantially perfect combustion—that is, if a large quantity of gas is supplied a correspondingly large amount of air is admitted, and if a medium or a minimum quantity of 15 gas is supplied a like quantity of air is admitted.

A single burner such as shown in Fig. 1 and above described is adapted for many uses, and can readily be conveyed from one place to another; but when a greater heat than can be 20 produced by a single burner is desired a number of the said burners may be grouped together, as shown in Fig. 5, where four burners are shown in plan view, the outer shell, a , being 25 cast in one piece and the caps a^6 in one piece. With this construction the damper is made as a single plate, d , provided with the series of holes 2 3 4, for the opening a^2 of each burner, as shown in Fig. 6.

30 The outer tube, b^3 , as herein shown, is cut, as at e , and bent outward to admit air between the inner and outer tubes.

In practice the reservoir will be located in the fire-pot of a stove or in a suitable casing 35 in which the heat is confined, so that the said reservoir becomes heated, thereby accelerating the action of the gas or vapor and producing a more active and perfect combustion.

In operation let it be supposed that gas has 40 been admitted to the burner and ignited. The gas is prevented from passing directly upward by the muffle, and consequently it must pass through the foraminous tubes; but it cannot pass through the inner tube, as a current of cold air is constantly passing up the 45 inner tube; hence it must pass through the sides of the outer tube. The current of cold air meets the muffle and is forced back, being made to seek another outlet, which is 50 through the sides of the foraminous tubes. The air commingles with the gas between the outer and inner tube and combustion takes place; but owing to the force of the cold air in the inner tube and the draft outward 55 through the tubes formed by the combustion of the gas some of the gas which is unconsumed is forced through the outer tube, where

it is consumed, the oxygen being supplied by the air on the outside of the burner. The flame arising from the combustion of the gas 60 is diffused or spread out laterally by the edge of muffle overlapping the outer tube, the said flame passing or folding over the muffle and concentrating or meeting substantially above the center of the said muffle, thereby obtaining 65 a maximum heat at that point.

I claim—

1. In a burner, the combination, with an inner and outer foraminous tube, of a base to support said tubes and composed of an outer 70 shell provided with openings for the admission of gas and air, an inner shell surrounding the said air-opening and forming with the outer shell a gas-chamber, and a cap for said chamber having gas-outlets to admit gas between the said tubes, substantially as described.

2. In a burner, the combination, with an inner and outer foraminous tube, of a muffle 80 covering said tubes, and a base provided with a gas-outlet to admit gas between the said tubes, and an air-passage to admit air to the inner tube, the products of combustion being caused by the said muffle to pass through the sides of the outer tube, substantially as and 85 for the purpose specified.

3. In a burner, the combination, with an inner and outer foraminous tube, of a muffle covering said tubes, and a base composed of an outer shell provided with openings for the 90 admission of gas and air, an inner shell surrounding the said air-opening and forming with the outer shell a gas-chamber, and a cap for said gas-chamber having gas-outlets to admit gas between the said tubes, substantially 95 as described.

4. In a burner, the combination, with an inner and outer foraminous tube, of a muffle covering said tubes, and a base composed of an outer shell provided with openings for the 100 admission of gas and air, an inner shell surrounding the said air-opening and forming with the outer shell a gas-chamber, and a cap for said gas-chamber having gas-outlets to admit gas between the said tubes, and with a 105 damper to regulate the supply of air to the burner, substantially as described.

In testimony whereof I have signed my name to this specification in the presence of two subscribing witnesses.

R. B. CARSLEY.
